ABSTRACT OF THE DISCLOSURE

In a fractional distillation system having two sources of liquid reflux streams which will partially vaporize when combined for such use, the flow rate and temperature of each of the liquid reflux streams are measured and signals representative thereof are applied to a computer-controller. The signals are combined to establish a signal representative of the preflash temperature of the combined stream, which is then employed in an internal reflux control to determine the required external reflux flow rate. The flow rate of one of the liquid streams is manipulated responsive to a desired control criteria while the flow rate of the other liquid stream is manipulated to provide the balance of the external reflux.

This invention relates to a control system for a fractional separation system utilizing two external reflux streams.

The utilization of conventional reflux control systems is not appropriate where the external reflux stream is obtained by combining two liquid streams from different sources which partially vaporize when combined as a single reflux stream at column pressure, as the temperature of the combined stream would not be indicative of the heat content of the combined stream.

Accordingly, it is an object of the invention to provide an improved control system for fractional separation systems utilizing two reflux streams. Another object is to maintain the desired internal reflux rate when utilizing two reflux streams of differing and variable temperatures and flow rates. Another object of the invention is to provide a means for controlling the total external reflux flow rate when utilizing two reflux streams. Other objects, aspects and advantages of the invention will be apparent from a study of the specification, the drawing and the appended claims to the invention.

In the drawings FIG. 1 is a diagrammatic representation of a fractionation system incorporating the present invention, and FIG. 2 is a diagrammatic representation of the components of a computer-controller which can be employed in the system of FIG. 1.

Referring now to FIG. 1, a multicomponent feedstock is passed through conduit 11 into fractional distillation column 12. While the invention is applicable to any fractional separation system employing two sources of external reflux, it will be described in terms of an ethylene fractionation column wherein the feed will generally contain primarily ethylene and ethane with small amounts of higher and lower boiling material. A bottoms stream containing ethane and any higher boiling material is withdrawn from column 12 by way of conduit 13. A vaporous overhead stream containing ethylene and any lighter boiling material is withdrawn from the upper portion of column 12 and passed by way of conduit 14 into knockout drum 15. Conduit 16, containing normally closed valve 17, communicates with the bottom portion of drum 15 for the removal of accumulated liquid as required.

A vaporous stream is withdrawn from the upper portion of drum 15 and passed by way of conduit 18 to the

2

inlet of first stage compressor 19. The outlet of compressor 19 is connected by conduit 21 to the inlet of second stage compressor 22, the outlet of which is connected by conduit 23 to the inlet of third stage compressor 24. The thus compressed vapor stream is passed through conduit 25 into and through indirect heat exchanger 26 wherein all or substantially all of the compressed stream is condensed. The resulting condensate is passed through conduit 27 into overhead accumulator 28. A first portion of the condensate is withdrawn from accumulator 28 by way of conduits 29 and 31 as an overhead liquid product of the system. A second portion of the condensate is passed by way of conduits 29 and 32 into and through indirect heat exchanger 33 for further cooling thereof. The cooled second portion of the condensate is then passed by way of conduits 34 and 35 into an upper portion of column 12 as a part of the external reflux therefor. A third portion of the condensate from accumulator 28 is passed by way of conduit 36 containing pressure-reducing valve 37 into high pressure flash tank 38.

Conduit 41 provides communication between conduit 23 and the inlet of reboiler 42 located in a bottom portion of column 12. Conduit 43 passes flashed vapor from the overhead of flash tank 38 to conduit 41. Liquid is withdrawn from the lower portion of flash tank 38 and passed by way of conduit 44, containing pressure-reducing valve 45, into low pressure flash tank 46. The flashed vapor is withdrawn from flash tank 46 and passed by way of conduits 47 and 21 to the inlet of second stage compressor 22. Conduit 51 connects the outlet of reboiler 42 to the inlet of indirect heat exchanger 52, the outlet of exchanger 52 being connected by conduit 53 to low pressure flash tank 46. A portion of the remaining liquid is withdrawn from tank 46 and passed by way of conduits 54 and 55 to indirect heat exchanger 56 wherein the liquid is vaporized. The resulting vapor is passed by way of conduits 57 and 14 to knockout drum 15. A second portion of the liquid withdrawn from flash tank 46 is passed by way of conduits 58 and 35 to the upper portion of column 12 as a portion of the external reflux for the column.

In addition to all of the variables normally encountered in a fractional distillation system, the system of FIG. 1 utilizes external reflux from two different sources and the temperature of each external reflux source varies independently of the other. The temperature variation problem is magnified by the use of the ethylene streams as a heating medium in exchangers 26, 33, 42, and 52, whereby the streams are cooled and/or condensed, and as a refrigerant in exchanger 56 whereby the stream is heated. In accordance with the present invention, the temperatures of the streams in conduits 34 and 58 are measured by temperature sensors 61 and 62, respectively, and signals 63 and 64 representative of the temperature measurements are transmitted by sensors 61 and 62 to computer-controller 65. The flow rates of the streams in conduits 34 and 58 are measured by flow sensors 66 and 67, respectively, and signals 68 and 69 representative of the flow measurements are transmitted to inputs of computer-controller 65. The output signals from flow sensors 66 and 67 are also applied to the measurement inputs of flow recorder-controllers 71 and 72, respectively. Flow controller 71 manipulates valve 73, located in conduit 34, to vary the flow rate of the external reflux stream therethrough responsive to a comparison of the actual flow rate as represented by the output of flow sensor 66 and the desired flow rate as represented by the setpoint signal 74 to controller 71. Similarly, controller 72 manipulates valve 75, located in conduit 58, to vary the flow rate of external reflux therethrough responsive to a comparison of the actual flow rate represented by the output of flow sensor 67 and the desired flow rate represented by setpoint signal 76 to controller 72. Computer-controller 65

establishes setpoint signals 74 and 76 responsive to the flow signals from sensors 66 and 67, the temperature signals from sensors 61 and 62, the manually adjusted inputs 77 and 78, and a temperature signal 79 from temperature sensor 81 located on conduit 14 upstream of conduit 57. The output signal from sensor 81 is representative of the temperature of the vaporous overhead stream being withdrawn from column 12.

The heat content of the streams in conduits 34 and 58 upstream of valves 73 and 75 is often such that while the streams are completely liquid upstream of valves 73 and 75, some vaporization will occur in the passage through the valves. In this circumstance, a measurement of the temperature of the combined external reflux in conduit 35 would not be meaningful with regard to heat content, and an internal reflux controller utilizing such a temperature measurement would be unsatisfactory. Also, a flow measurement of a partially vaporized stream would not be meaningful. A meaningful temperature T_r can be defined as the temperature which the resultant stream would have upon the combination of the two reflux streams under conditions to maintain the result stream completely in the liquid phase. The value of T_r can be obtained from the equation:

$$T_r = \frac{F_1 T_1 + F_2 T_2}{F_1 + F_2}$$

where:

T_1 is the temperature of the liquid stream in conduit 34 upstream of valve 73,

T_2 is the temperature of the liquid stream in conduit 58 upstream of valve 75,

F_1 is the flow rate of the liquid stream in conduit 34, and F_2 is the flow rate of the liquid stream in conduit 58.

The internal reflux, R_i , in column 12 can now be defined as

$$R_i = R_e (1 + K_1 (T_o - T_r))$$

where:

R_o is the sum of F_1 and F_2 ,

T_o is the temperature of the vaporous stream being withdrawn from the overhead of column 12, and

K_1 equals the ratio of the specific heat of the combined external reflux to the heat of vaporization of the liquid on the top tray of column 12.

This equation can be rearranged for computer solution as

$$R_e = \frac{R_i}{1 + K_1 (T_o - T_r)}$$

The rate of flow of the primary external reflux stream F_2 through conduit 58 can be manipulated in a constant ratio relationship with the desired internal reflux, R_{ID} ; that is,

$$F_2 = K_2 R_{ID}$$

where K_2 is a constant having a value less than unity. The values of K_2 and R_{ID} can be applied to computer-controller 65 as the setpoint inputs 78 and 77. The rate of flow of the secondary reflux stream F_1 through conduit 34 is varied to provide the balance of the required external reflux, which is computed from the desired internal reflux; that is,

$$F_1 = R_e - K_2 R_{ID}$$

Referring now to FIG. 2, temperature signals 63 and 64 are applied to first inputs of multipliers 101 and 102, respectively. Flow signals 68 and 69 are applied to the second inputs of multipliers 101 and 102, respectively, and also to inputs of adder 103. The outputs of multipliers 101 and 102 are applied to respective inputs of adder 104. The output of adder 103 is connected to the divisor input of divider 105, while the output of adder 104 is applied to the dividend input of divider 105. Temperature signal 79 is applied to the minuend input of

subtractor 106, while the output of divider 105 is applied to the subtrahend input of subfactor 106. The output of subtractor 106 is applied to a first input of multiplier 107, a signal representative of K_1 being applied to the second input of multiplier 107. The output of multiplier 107 is connected to one input of adder 108, a signal representative of unity being applied to a second input of adder 108. A signal 77 representative of the desired internal reflux, R_{ID} , is applied to the dividend input of divider 109 and to a first input of multiplier 110. The output of adder 108 is connected to the divisor input of divider 109. The output of divider 109 is representative of the required external reflux flow rate R_e and is applied to the minuend input of subtractor 111. A signal 78, representative of K_2 is applied to a second input of multiplier 110. The output of multiplier 110 designated as $F_{2(SP)}$ is applied to the setpoint input of controller 72 and to the subtrahend input of subtractor 111. The output of subtractor 111 designated as $F_{1(SP)}$ is applied to the setpoint input of controller 71.

The mathematical operation of computer-controller 65 in this novel control system may be summarized as follows. From measurements of stream flow rates and temperatures, the meaningful preflash temperature, T_r , of the combined reflux stream is computed. From this value of T_r , the measured overhead vapor temperature, T_o , and the desired (setpoint) value of internal reflux, R_{ID} , the required external reflux flow rate, R_e , is computed. Further, specifying (by K_2) that the external reflux supplied by conduit 58, F_2 , be in a fixed ratio to the specified internal reflux, R_{ID} , the value of $F_{2(SP)}$ is calculated and subtracted from the total external reflux, R_e , to produce the value of external reflux required through conduit 34, $F_{1(SP)}$. These two setpoint values, $F_{1(SP)}$ and $F_{2(SP)}$, are supplied by signal lines 74 and 76 to flow controllers 71 and 72, respectively, so as to provide combined-stream reflux flow and enthalpy control, whereby the degree of regulation of the component-separation capacity of fractionation column 12 is greatly enhanced.

While the control of the flow rate of the second liquid stream through conduit 58 has been described in terms of a ratio to the desired internal reflux, it is within the contemplation of the invention to utilize any other desired criteria for the control of the second liquid stream, for example, a constant flow rate or in a ratio to the flow rate of the first liquid stream, or a requirement of another portion of the process.

Reasonable variations and modifications are possible within the scope of the foregoing disclosure, the drawing and the appended claims to the invention.

We claim:

- Apparatus comprising a fractional separation column; means for introducing into an intermediate section of said column a multicomponent feed stream; means for withdrawing an overhead stream from an upper section of said column; means for withdrawing a bottom stream from a bottom section of said column; a first source of a first liquid stream having a variable temperature; a second source of a second liquid stream having a variable temperature; first conduit means connected between said first source and an upper portion of said column; second conduit means connected between said second source and an upper portion of said column; a first valve means in said first conduit means for the regulation of the flow rate of said first liquid stream through said first conduit means; a second valve means in said second conduit means for the regulation of the flow rate of said second liquid stream through said second conduit means; means for measuring the temperature of said first liquid stream in said first conduit means upstream of said first valve means and establishing a first signal representative thereof; means for measuring the temperature of said second liquid stream in said second conduit means upstream of said second valve means and establishing a second signal representative thereof; means for establishing a third signal representative of the flow rate of said first liquid stream

through said first conduit means; means for establishing a fourth signal representative of the flow rate of said second liquid stream through said second conduit means; means responsive to said first, second, third and fourth signals to establish a fifth signal representative of the temperature of the liquid combined stream which would result from combining said first liquid stream and said second liquid stream; means for establishing a sixth signal representative of the desired internal reflux of said column; means responsive to said fifth and sixth signals to establish a seventh signal representative of the rate of flow of external reflux required to produce said desired internal reflux; means for manipulating said second valve to control the flow rate of said second liquid stream responsive to a desired criteria; and means responsive to said seventh signal and the flow rate of said second liquid stream for manipulating said first valve to control the flow rate of said first liquid stream to provide the balance of the required external reflux.

2. Apparatus in accordance with claim 1 wherein said means for establishing a fifth signal comprises means responsive to said first and third signals to establish an eighth signal representative of the multiplication product of said first and third signals, means responsive to said second and fourth signals for establishing a ninth signal representative of the multiplication product of said second and fourth signals, means responsive to said eighth and ninth signals to establish a tenth signal representative of the sum of said eighth and ninth signals, means responsive to said third and fourth signals to establish an eleventh signal representative of the sum of said third and fourth signals, means responsive to said tenth and eleventh signals to establish said fifth signal representative of the ratio of said tenth signal to said eleventh signal.

3. Apparatus in accordance with claim 2 wherein said means to establish a seventh signal comprises means to establish a twelfth signal representative of the temperature of said overhead stream, means responsive to said fifth and twelfth signals for establishing a thirteenth signal representative of the difference between said fifth and twelfth signals, and means responsive to said sixth and thirteenth signals to establish said seventh signal representative of the required external reflux for said column.

4. Apparatus in accordance with claim 2 wherein said means for manipulating said second valve comprises means for establishing a twelfth signal representative of the desired ratio of the flow rate of said second liquid

stream to said desired internal reflux; means responsive to said sixth and twelfth signals to establish a thirteenth signal representative of the multiplication product of said sixth and twelfth signals; means for manipulating said second valve responsive to said thirteenth signal; and means responsive to said seventh and thirteenth signals for establishing a fourteenth signal representative of the difference between said seventh and thirteenth signals; and wherein said first valve means is manipulated responsive to said fourteenth signal.

5. Apparatus in accordance with claim 1 wherein said means for manipulating said second valve comprises means for establishing an eighth signal representative of the desired ratio of the flow rate of said second liquid stream to said desired internal reflux; means responsive to said sixth and eighth signals to establish a ninth signal representative of the multiplication product of said sixth and eighth signals; and means for manipulating said second valve responsive to said ninth signal.

20 6. Apparatus in accordance with claim 1 further comprising means for dividing said overhead stream into at least three fractions; means for passing a first one of said fractions through a first heat exchanging path to obtain said first liquid stream; means for passing a second one of said fractions through a second heat exchanging path to obtain said second liquid stream; and means for withdrawing a third one of said fractions as a product.
